UNITED STATES PATENT OFFICE

HAROLD D. BROWN, OF LOS ANGELES, CALIFORNIA

DESIGN FOR ROOFING

Application filed July 7, 1930. Serial No. 36,282. Term of patent 14 years.

To all whom it may concern:

Be it known that I, HAROLD D. BROWN, a citizen of the United States, residing at Los Angeles, in the county of Los Angeles and State of California, have invented a new, original, and ornamental Design for Roofing, of which the following is a specification, reference being had to the accompanying drawing, forming part thereof.

Fig. 1 is a perspective view of a section of a shingled roof showing my new design.

Fig. 2 is a view showing a fragmentary portion of the shingled roof shown in Fig. 1.

I claim:

The ornamental design for roofing, as shown.

HAROLD D. BROWN.
